UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

SUPERHEATER-BOILER.

1,150,944.

Specification of Letters Patent. Patented Aug. 24, 1915.

Application filed July 26, 1913. Serial No. 781,300.

To all whom it may concern:

Be it known that I, DAVID S. JACOBUS, a citizen of the United States, residing at Jersey City, in the county of Hudson and 5 State of New Jersey, have invented certain new and useful Improvements in Superheater Boilers, of which the following is a specification.

My invention relates to that class of water 10 tube boilers having two or more transverse steam and water drums connected by banks of tubes to corresponding mud drums, the tubes being either straight throughout their 15 length or with curved or bent ends, and is designed to provide a boiler of this class with a superheater located at the rear of the first bank of tubes.

The invention will be understood by reference to the accompanying drawings in 20 which—

Figure 1 is a sectional side elevation of one embodiment of my invention; Fig. 2 an enlarged view of a part thereof, and Fig. 3 a section on the plane of the line 3—3 of 25 Fig. 2.

Similar reference numerals indicate similar parts in the several views.

A boiler containing the present invention may have two or more banks of tubes. The 30 design shown has three banks designated by the numerals 1, 2 and 3, each bank having five rows of tubes. The tubes are straight throughout their length and are expanded at their upper ends into transverse steam and water drums 4, 5 and 6, and at their 35 lower-ends into corresponding transverse mud drums 7, 8 and 9 respectively. The mud drums are supported above the floor of the setting so that the soot and dust which falls from the tubes or from the hot, gases, 40 will be deposited in the space at the bottom and at the sides of the drum, from whence it can be readily removed through suitable doors.

The steam and water drums are connected 45 by steam circulators 10 and by water circulators 11. The mud drums are connected by circulators 12. In the space between the first and second banks of tubes are two rows 50 of tubes 13 and 14, which tubes are bent at their upper and lower ends and the former expanded into the drums 4 and 7 of the first banks of tubes, and the latter into the drums 5 and 8 of the middle bank. These tubes 55 support a vertical baffle 15 which forms a

continuation of a wall 16 extending upwardly from the floor to said baffle. In the space between the second and rear banks of tubes are two rows of tubes 17 and 18, the former being expanded into the drums 5 and 8 of the middle bank, and the latter into the drums 6 and 9 of the rear bank of tubes. The tubes 17 and 18 support a baffle 19 extending downwardly from the rear steam and water drum 6. The baffles 15 and 19 extend across the boiler setting from side to side. In order to secure an efficient heat absorption of the gases in passing over the tubes, the gases are deflected into the banks of tubes and across the tubes by horizontal 60 baffles 20 supported upon suitable brackets between the second and third banks of tubes; by a baffle 21 extending laterally from the vertical baffle 15; and by inclined shelves 20' extending from the vertical baffle 15, and 65 also placed in the first and rear passes.

At the rear of the first bank of tubes, in the space between said bank and the rows of tubes 13, is a superheater consisting of a series of U-shaped tubes 23 lying side by 70 side in vertical planes and expanded at their lower ends into cross boxes 24 and 25. A pipe 26 leads from the middle steam and water drum to box 24. A suitable outlet connection is provided for box 25. These 75 boxes are placed in the lower part of the space and are substantially horizontal and extend from one side to the other of the boiler setting. To protect the boxes from being over-heated I introduce a baffle 27, made up of suitable tiling, extending 80 completely across the setting from side to side, so that the only way in which the hot gases can act directly on the superheater is by passing above the baffle. The lower part of 85 the tiling rests on cast iron saddles 28 which are supported upon the lower curved ends of tubes 13. These cast iron saddles are made so that they do not reduce the open space 90 between the tubes on which they rest, and the openings between the saddles and the tubes serve a useful purpose in allowing 95 soot and dust which collects on top of the mud drum to fall down into the space at the rear and below the drum, when such 100 soot and dust is blown to the rear by means of a steam or air lance. A portion of the tiling is supported by the rear line of straight boiler tubes of the first bank. The 105 superheat can be adjusted by altering the 110

height of the protecting baffle 27 without interfering with the capacity or efficiency of the boiler.

The advantage of placing the superheater in the position shown, is that the maximum obtainable superheat may be secured with a given amount of superheating surface, and the superheater tubes at the same time will be protected from over-heating, as the hot gases must first pass through the first bank of boiler tubes before striking the superheater. Further, the superheater is placed in a position where the lower part of the boxes are readily accessible and the arrangement is such that the ends of the superheater tubes where they enter the boxes may be readily inspected, and where internal cores are used the cores may be withdrawn from the tubes after the superheater is in place 20 within the boiler setting.

The dust which falls from the exterior surface of the superheater will find its way to the space at the bottom of the boiler at the rear of the mud drum of the first bank of tubes, where it will not interfere with the action of the superheater or boiler, and the arrangement of the protecting tiling 27 is such that any dust which collects on top of the mud drum of the first bank of tubes may, 30 as already stated, be blown by means of a steam or air lance to the rear of the mud drums, and will fall through the openings 28 between the saddle pieces 28 into the space at the rear and below this mud drum, in 35 which space it may be cleaned out at intervals.

A boiler for the utilization of waste heat is shown, the gases entering through the flue 29, but it is applicable to any class of service. The hot gases first make a single pass across the lower part of the first bank of tubes, thence over the superheater tubes and are then deflected, by baffle 21, between the upper portion of the tubes of the first bank, 45 thence across and down over the tubes of the second bank, and thence across and upwardly over the tubes of the third bank to the stack outlet 30. In their general down and up course along the tubes of the middle and rear banks the gases are made to cross and recross the tubes of said banks by means of the cross baffles 20 and inclined shelves 20'.

As shown in the drawing, the space between the first bank of tubes and the baffle 55 15 is wider than the spaces between the second and third banks of tubes and the vertical baffles. This wider space enables a man to enter alongside the superheater for the purpose of cleaning or brushing down the 60 superheater surfaces by hand.

What I claim and desire to secure by Letters Patent of the United States is:—

1. A water tube boiler having a plurality of transverse steam and water drums connected by banks of tubes to corresponding

transverse mud drums, and a superheater with vertical loops at the rear of the first bank of tubes, there being a protected space back of the first bank of tubes, and transverse boxes into which said tubes are expanded, said boxes being in proximity to the lower part of the first bank and within said protected space. 70

2. A water tube boiler having a plurality of transverse steam and water drums connected by banks of tubes to corresponding transverse mud drums, vertical baffles between the banks of tubes, and a superheater with vertical loops at the rear of the first bank of tubes, there being a protected space 80 back of the first bank of tubes, and transverse boxes into which said tubes are expanded, said boxes being in proximity to the lower part of the first bank and within said protected space. 85

3. A water tube boiler having a plurality of transverse steam and water drums connected by banks of tubes to corresponding transverse mud drums, a superheater at the rear of the first bank of tubes having cross 90 boxes with loops extending upwardly therefrom, and baffles at the front and back of said boxes to protect them from the direct impingement of the hot gases. 95

4. A water tube boiler having a plurality of transverse steam and water drums connected by banks of tubes to corresponding transverse mud drums, a superheater at the rear of the first bank of tubes having cross boxes with loops extending upwardly therefrom, and baffles at the front and back of said boxes to protect them from the direct impingement of the hot gases, the front baffle being supported on the boiler tubes. 100

5. A water tube boiler having a plurality of transverse steam and water drums connected by banks of tubes to corresponding transverse mud drums, two rows of tubes between the first and second banks one of said rows being expanded into the drums of the first bank and the other into the drums of the second bank of tubes, a baffle supported by said tubes, a superheater at the rear of the first bank of tubes between said bank and said baffle, said superheater comprising cross boxes in proximity to the mud drum of the first bank of tubes, and U-shaped tubes expanded into said boxes, said U-shaped tubes being below the upper edge of the baffle. 110 115

6. A water tube boiler having a plurality of transverse steam and water drums connected by banks of tubes to corresponding transverse mud drums, two rows of tubes between the first and second banks one of said rows being expanded into the drums of the first bank and the other into the drums of the second bank of tubes, a baffle supported by said tubes, a superheater at the rear of the first bank of tubes between said 120 125

- bank and said baffle, said superheater comprising cross boxes in proximity to the mud drum of the first bank of tubes, and U-shaped tubes expanded into said boxes, and a baffle in front of said boxes, said baffle being supported by one of said rows of tubes.
7. A water tube boiler having a plurality of transverse steam and water drums connected by banks of tubes to corresponding transverse mud drums, a row of tubes between the first and second banks of tubes said row being expanded into drums of the first bank, a superheater in the space between the first bank of tubes and said row of tubes, said superheater comprising cross boxes in the lower part of said space, and a baffle resting upon said row of tubes and extending upwardly to protect said boxes against direct impingement of the hot gases.
8. A water tube boiler having a plurality of transverse steam and water drums connected by banks of tubes to corresponding transverse mud drums, vertical baffles between the banks of tubes, the space at the rear of the first bank of tubes being wider than the spaces between the other banks of tubes and said vertical baffles, and a superheater in the space at the rear of the first bank of tubes, and a shelf above said superheater extending from the adjacent baffle toward the first bank of tubes.
9. A water tube boiler having a plurality of transverse steam and water drums connected by banks of tubes to corresponding transverse mud drums, baffles between said banks of tubes, a superheater between the first bank of tubes and the first baffle, and baffle shelves for directing the flow of the gases so as to make a single pass across the boiler tubes of the first bank, and thence over the superheater tubes, and from thence back over the same boiler tubes.
10. A water tube boiler having a plurality of transverse steam and water drums connected by banks of tubes to corresponding transverse mud drums, vertical baffles between the banks of tubes, a superheater at the rear of the first bank of tubes having cross boxes with loops extending upwardly therefrom, a baffle between the first bank of tubes and the boxes to protect said boxes from the direct impingement of the hot gases, said baffle being arranged so that there will be openings beneath the baffle from which soot or dust may be blown in cleaning the boiler surfaces.
11. A water tube boiler having a plurality of transverse steam and water drums connected by banks of tubes to corresponding transverse mud drums, saddle pieces resting on boiler tubes, a row of tubes between the first and second banks, a superheater in the space between the first bank of tubes and said row of tubes, and a baffle supported on said saddle pieces to protect the cross boxes of said superheater.

In testimony whereof I have hereunto signed my name in the presence of two subscribing witnesses.

DAVID S. JACOBUS.

E. P. TERRY.

It is hereby certified that in Letters Patent No. 1,150,944, granted August 24, 1915, upon the application of David S. Jacobus, of Jersey City, New Jersey, for an improvement in "Superheater-Boilers," an error appears in the printed specification requiring correction as follows: Page 2, line 32, for the reference-numeral "28" read *28'*; and that the said Letters Patent should be read with this correction therein that the same may conform to the record of the case in the Patent Office.

Signed and sealed this 28th day of September, A. D., 1915.
